UNITED STATES PATENT OFFICE.

WILLIAM M. SCHOLL, OF CHICAGO, ILLINOIS.

ARCH-SUPPORT.

1,152,556.

Specification of Letters Patent. Patented Sept. 7, 1915.

Application filed January 3, 1913. Serial No. 739,983.

To all whom it may concern:

Be it known that I, WILLIAM M. SCHOLL, a citizen of the United States, residing at Chicago, in the county of Cook and State of Illinois, have invented certain new and useful Improvements in Arch-Supports, of which the following is a specification.

My invention relates to improvements in arch supports, and in some of its features 10 more particularly to arch supports for correcting the foot-trouble medically known as metatarsalgia. This condition may be briefly described as a breaking down of the transverse arch of the foot. Usually the 15 ligaments are strained, elongated or displaced; the falling of the transverse arch throws undue pressure on the second, third and fourth metatarsal bones; the corresponding phalanges tend to become unduly 20 elevated or "cocked;" the first and fifth metatarsal-phalangeal articulations are apt to be laterally displaced; the digital nerve is frequently affected; and the anterior region is subject to excruciating pain. Me- 25 chanical uplift of the transverse arch is ad- vantageous in relieving the condition, and oftentimes in effecting a permanent cure; but the provision of an effective appliance prop- erly to secure such uplift is one of peculiar 30 difficulties owing to the requisite changes in the necessary localization of elevation as the condition of the foot changes; and owing further to the nicety with which the sup- 35 porting surface must be located with re- spect to the articulations and secure the de- sired orthopedic effect.

A salient object of my invention is to pro- vide an instep arch construction particularly adapted to the treatment of this trouble; 40 although in some of its features it is generally applicable to instep arch supports wherein a metallic arch-plate for support of the longitudinal arch is provided in conjunction with a cover piece which positions 45 it in the shoe.

In the drawings wherein I have illus- trated an embodiment of my invention Figure 1 is a plan view of the under side of an arch support constructed in accordance with 50 my invention; Fig. 2 is a similar view with the metallic plate removed, showing the cover beads and its attachment to the strip; Fig. 3 is a section on line 3—3 of Fig. 1; Fig. 4 is a transverse section on line 4—4 of 55 Fig. 1; Fig. 5 is a sectional detail on line

5—5 of Fig. 1; and Fig. 6 is a sectional de- tail on line 6—6 of Fig. 1.

In the drawings, 10 indicates a position- ing member, in the form of a piece of leather which acts as a cover piece for the metallic 60 arch-plate. This leather cover piece is in- tended to fit snugly in the heel portion of the shoe to give position to the metallic parts of the support. The cover piece 10 as shown is preferably of such size and shape 65 that it may extend from the extreme heel of the shoe, where its rear curved edge makes contact with the shoe counter, forwardly to underlie the ball of the foot, the forward end of the cover piece being skived in the 70 usual manner, and its inner lateral edge be- ing extended well up the inner side of the plantar-arch.

11 indicates a metallic arch-plate to be se- cured to and carried by cover piece 10, 75 thereby to be positioned in the shoe.

Throughout the heel portion and shank portion the metallic plate 11 is shaped for general conformity with the corresponding portions of the plantar surfaces of the foot; that is to say it has appropriate longitudi- 80 nal and transverse curvatures to conform the heel and shank portions of the metal plate to the main arch of the normal human foot, and preferably, I make such plate to under- 85 lie the bony structure of the foot from the bearing point of the os-calsis to a point be- neath the metatarsal bones and I prefer that the plate of sufficient width to support all of the cuneiform bones,—although the rear- 90 ward and transverse extent of the heel and shank portions of the arch-plate may be var- ied to suit particular requirements and de- 95 mands. This structure of the plate provides an elevated portion thereof along a line gen- erally definable as extending from the inner side of the heel of the foot to the base of the great toe, and along this general line I pro- 100 vide, in addition to the normal curvatures of the plate, a receiving channel 12, preferably formed by depressing the metal of the plate as best shown in Figs. 3 and 4. The ends of this depressed channel may merge into the extreme portions of the plate so that when the plate is in use the channel does not inter- 105 fere with its insertion into the shoe.

Attached to the under side of the cover piece 10 is a flexible metallic strip 13, se- cured to the leather as by rivets 14 and adapted to lie in the channel 12 of the arch- 110

plate. Said strip 13 primarily affords a guiding and anchorage piece for the reception of connecting parts by which the arch-plate 11 is movably or shiftably connected with the cover piece 10. It is advantageous that the strip 13 be continuous in order positively to space the connecting members apart and to stiffen the cover piece somewhat in a longitudinal direction and it is preferable 10 that the strip be as thick as the channel is deep, so that the cover piece lies smoothly over the grooved part of the plate. Adjacent its rear end the strip 13 is provided with a boss or guide lug 15 adapted to engage in a longitudinal slot 16 formed therefor in the bottom surface of channel 12, and said boss is centrally threaded to receive a retaining screw 18 the head of which extends over the edges of slot 16 to clamp the 15 arch-plate to the strip 13 in adjusted position. Similar provision may be made at the front end of strip 13, but I prefer that the adjusting means at the front end of the strip shall admit of universal adjustment 20 of the front end of the plate beneath the cover piece. To this end I mount an eccentric disk 20 upon stud 21 which is secured to the front end of the strip 13, said disk fitting transversely in a slot 16' in the bottom of the depressed channel 12 and said stud 21 receiving screw 22 extending sufficiently beyond the edge of the eccentric disk to clamp the disk, the metal arch-plate and the cover piece in adjusted relation to 25 each other. It will be seen that the slots 16—16' permit the plate 11 to be longitudinally adjusted while the disk connection permits the front end of the arch-plate to be adjusted laterally somewhat with respect to 30 the leather cover piece accordingly as the disk is thrown eccentrically to its stud 21, and of course the strip 13 should have such play within the depressed channel 12 as to accommodate any adjustment of the arch-plate relative to strip 13 within the range of throw of the disk, the depressed channel 12 to this end being preferably slightly tapered 35 from front to rear as shown in Fig. 1.

It will be observed that the construction 40 described permits the front end of the arch-plate to be universally adjusted with respect to the cover piece and this is of advantage in many forms of arch support, enabling the metallic plate member to be brought exactly in the proper position with respect to the foot of the wearer without detaching it from the cover piece.

In the treatment of metatarsalgia I find 45 it to be important that the first and fifth metatarsal-phalangeal articulations, which should normally bear the brunt of the foot pressure, shall be left free from substantial elevation, in order that no undue strain may be thrown thereon, and for relief of the pressure which the improper condition of

the foot causes to be thrown upon the second, third and fourth articulations, the supporting elevation beneath these articulations should be carried well forward toward the heads of the corresponding metatarsal bones. 50 I find it advantageous so to shape the front end of the arch plate 11 used in such cases to provide two cut-away portions or recesses 26 and 27 respectively to receive the heads of the first and fifth metatarsal bones, and 55 to provide between said two recesses a longitudinally projected tongue 28 in which is formed additionally to the normal curvatures of the arch-plate, a hump or convex protuberance 29 the effect of which is to 60 force upward the fleshy portions of the foot immediately underlying the second, third and fourth metatarsal bones. This boss should be carried well forward into the tongue 28 so that the elevating effect may 65 be applied as close as possible to the heads of the affected metatarsal bones without directly underlying the heads of said bones with the edges of said metal plate. In connection with this arrangement the adjustability of the arch-plate with respect to the cover piece is of particular advantage, as a very slight change in adjustment of the position of the hump 28 will vary to a material degree the effectiveness of the appliance to 70 restore the broken transverse arch although in most instances such adjustments are relatively so slight that they do not unduly disturb the relation of the shank of the plate to the foot of the wearer. Furthermore in 75 cases of metatarsalgia a gradual change in the condition of the foot due to its improvement under treatment often necessitates readjustment from time to time of the location of the transverse hump with respect to 80 the foot of the wearer, it being commonly the case that the painfulness of the foot in the early stages of treatment necessitates the placement of the hump farther back toward the instep than is the case when the treatment has proceeded farther and the swelling and pain have diminished. Furthermore, 85 I find that the relative lengths of the cover piece and arch plate must sometimes be varied, and to insure that a proper relation of 90 these parts may be easily attained I preferably make the cover piece for each size of arch-plate of that length which is about the maximum that may be required for the given length of arch plate, and then in the heel portion of the cover piece I form size indicating marks or curves 30, preferably in the form of cuts or score-marks effectively attenuating the leather along the curved lines, and score-marks preferably extending from 95 the under side of the leather almost to the top surface thereof so that the leather may readily be trimmed down. In practice since the cover pieces are intended to fit with reasonable accuracy in ordinary shoes, it is pref- 100

erable to make the score lines 30 at such distances apart as to represent approximately the usual variations in shoe sizes.

While I have herein described in some detail a particular embodiment of my invention it will be apparent to those skilled in the art that changes might be made in the detail of construction without departure from my invention and within the scope of the appended claims.

What I claim is:

1. An arch-plate adapted to underlie the ball of a human foot having its upper surface curved for general conformity with the curvatures of the appropriate plantar surfaces of the foot, and having a non-flexible and non-resilient front end shaped to provide a projecting tongue to underlie the forward portions of the central metatarsal bones and to leave free from such support the heads of the first and fifth metatarsal bones, said plate having formed therein, in addition to its normal curvature, a transverse hump for support of the central metatarsal bone, said hump extending into the tongue.

2. In an arch support the combination of a cover piece, a plate adapted to underlie the ball of a human foot having its upper surface generally curved to conform to the adjacent portions of the plantar surface of the foot, the front edge of said plate being provided, in addition to its normal curvatures, with a transverse hump to support the middle metatarsal bones, and means connecting said plate to said cover piece for adjustment of said plate both longitudinally and transversely with respect to the cover piece.

3. In an arch support, the combination of a leather cover piece, shaped to fit the heel of the shoe and extending thence along the inner and outer sides of the shoe to a point approximately at the ball of the foot, and having an extension to extend up the inside curve of the shank of the foot, a metal arch plate shaped to conform substantially to the curvatures of the under side of the foot and to extend from the bearing point adjacent the heel of the foot at one end to a bearing point adjacent the ball of the foot at the other end, and transversely to conform to the curvature of the high arched point or surface underlying the scaphoid and adjacent cuneiform bones and devices carried by said cover piece for connecting the same to the plate at longitudinally spaced points, one of said connecting devices providing longitudinal movement of said arch plate with respect to the cover piece and the other providing movement in all directions in the plane of said plate.

4. In an arch support the combination of a leather cover piece, shaped to fit the heel of the shoe and extending thence along the

inner and outer sides of the shoe to a point approximately at the ball of the foot, and having an extension to extend up the inside curve of the shank of the foot, a metal arch plate shaped to conform substantially to the curvatures of the under side of the foot and to extend from the bearing point adjacent the heel of the foot and to one end to a bearing point adjacent the ball of the foot at the other end, and transversely to conform to the curvature of the high arched point or surface underlying the scaphoid and adjacent cuneiform bones, and adjusting means interposed between the forward end of said arch plate and the superposed portion of the cover piece for effecting adjustment of said portion of said arch plate with respect to the coöperating portion of the leather cover piece in all directions in the plane of said plate.

5. In an arch support the combination of a leather cover piece, metal anchorage members secured thereto at front and rear portions thereof, a metal arch-plate having openings therein, and means secured to said anchorage members and engaging said openings in the arch-plate for adjusting the rear of the arch-plate longitudinally with respect to the cover piece and the front end in all directions in the plane of the plate.

6. In an arch support the combination of a leather cover piece, anchorage strips secured thereto, an arch-plate having therein a channel to receive the strip, and means connecting the strip and arch-plate for relative longitudinal adjustment.

7. In an arch support, the combination of a leather cover piece shaped to fit the shank and heel of a shoe, an arch plate shaped substantially to conform to the shank portion of a human instep to extend from the point adjacent the heel to a point adjacent the ball of the foot, said plate having apertures at longitudinally spaced points therein and connecting devices carried by the cover piece engaging, and relatively movable with respect to, the apertures in the plate, one of said connecting devices providing longitudinal movement of said arch plate with respect to the cover piece and the other providing movement in all directions in the plane of the plate.

8. In an arch support, the combination of a leather cover piece, adapted to interfit with the heel and shank of a shoe, an arch plate having alining openings therein at different longitudinal points, and the rear opening being longitudinally extended and the front opening being substantially circular, a post connected to the leather cover piece engaging the extended rear opening in the plate and a rotatable part carried by the leather cover piece, engaging the circular opening in the plate, whereby the front end of the arch plate is movable in

all directions in the plane of the plate with respect to the cover piece that the rear end may slide longitudinally with respect thereto.

5. 9. In an arch support, the combination of a leather cover piece, a longitudinally extending anchorage strip secured thereto, an arch plate having therein a longitudinal channel to receive said strip, said channel tapering from its front to its rear end

and means for connecting said strip and channeled plate permitting longitudinal and lateral adjustment of the front end of said plate with respect to the cover piece.

In testimony whereof I hereunto set my 15 hand in the presence of two witnesses.

WILLIAM M. SCHOLL.

In the presence of—

W. LENN ALLEN,
MARY F. ALLEN.
